UNITED STATES PATENT OFFICE.

WLADIMIR J. POLYDOROFF, OF CHICAGO, ILLINOIS, ASSIGNOR TO JOHNSON-WILLIAM-
SON LABORATORIES, INC., OF CHICAGO, ILLINOIS, A CORPORATION OF ILLINOIS.

DESIGN FOR A RADIOPHORN.

Application filed September 5, 1925. Serial No. 14,714. Term of patent 3½ years.

To all whom it may concern:

Be it known that I, WLADIMIR J. POLYDOROFF, formerly a subject of the Czar of Russia, who have declared my intention to become a citizen of the United States, residing at Chicago, in the county of Cook and State of Illinois, have invented a new and original Design for Radiophorns, of which the following is a specification, reference

being had to the accompanying drawing, forming part thereof.

The figure is a view in elevation of a horn showing my new design.

I claim:

The ornamental design for a radiophorn, as shown.

WLADIMIR J. POLYDOROFF.
